UNITED STATES PATENT OFFICE

2,569,759

SPRAY-PRODUCING APPARATUS FOR LIQUIDS

Geoffrey Meredith Hall, Oldham, England

Application January 20, 1948, Serial No. 3,193
In Great Britain January 28, 1947

8 Claims. (Cl. 299—63)

1

This invention relates to spray-producing apparatus and more particularly to portable apparatus for liquids, of the kind in which the liquid is centrifugally dispersed.

The object of the invention is to provide a new and improved construction of centrifugal spraying apparatus for liquids in which a high degree of atomisation is obtainable, less air accompanies the atomised liquid, less of the atomised liquid is lost, its application to the surface meets less resistance, the surrounding atmosphere is less polluted by the atomised liquid and more even dispersion and distribution of the atomised liquid on the surface to be sprayed is obtainable.

According to the invention a spray producing apparatus for liquids comprises a cup-like feed centrifuge adapted to rotate about a substantially vertical axis and having its mouth directed upwardly, a cup-like atomising centrifuge arranged to rotate about an axis at right angles to the axis of the said cup-like feed centrifuge and disposed with a part of the rim of said cup-like feed centrifuge within it, a cup-like controlling centrifuge adapted to rotate about an axis lying substantially in the same plane as the axis of the cup-like feed centrifuge and passing through the axis of said cup-like atomising centrifuge, disposed to surround part of the rim of said cup-like atomising centrifuge and having an aperture in its base intersected by the plane in which lies the rim of the atomising centrifuge, a casing surrounding all the said centrifuges and having an orifice also intersected by the plane in which lies the rim of the atomising centrifuge and in alignment with the aforesaid aperture so that liquid may pass therethrough after ejection from the rim of the atomising centrifuge and after passing through the said aperture in the controlling centrifuge, means for driving all said centrifuges, and means for feeding liquid to said cup-like centrifuge.

Referring to the accompanying drawings—

Fig. 1 shows a part-section, part-elevation view of a liquid spray-producing apparatus in accordance with the invention;

Fig. 2 shows an enlarged view of part of Fig. 1;

Fig. 3 shows a sectional plan view along the line AA of Fig. 2, and

Fig. 4 shows a sectional view along the line BB of Fig. 3, looking in the direction of the arrows.

In carrying the invention into effect according to one form by way of example, a portable liquid spray-producing apparatus intended for paint

2

spraying, see the accompanying drawings, comprises a container 1 for the paint the mouth of which is turned outwards at 2 to fit within a corresponding rim 3 of a cap 4 to which it is removably attached by toggle clamps of well-known type (not shown). The cap 4 carries a vertical tube 5 forming the lower part of a feed tube which terminates at its lower end a little way above the base of the container, and at its upper end within the neck of the container. The feed tube 5 is attached to the cap 4 by means of a three-armed spider 6. A collinear tube 7 forming the upper part of the feed tube is carried above the tube 5 by a flexible three-armed spider 8 attached to the cap 4, and is adjustable in position as hereinafter described to provide a gap 9 between its lower end and the upper end of the tube 5 or to be lowered to close this gap.

Within the tube 5 and extending to above the upper end of the collinear tube 7 is a vertical shaft 10 the lower portion of which is provided with a screw thread 11 thus forming with the tube 5 an Archimedean screw. The upper end of the shaft is joined by a rubber coupling 12 and bush 13 to a vertical spindle 14 carrying a rigidly-attached bevel gear wheel 15 contained in an approximately spherical gear-box casing 16. This wheel rotates in a horizontal plane and is in engagement with a second bevel-gear wheel 17 rotatable in a vertical plane. Gear wheel 17 is driven by a horizontal spindle 18 on which it is held by a spring clip 19. Spindle 18 is carried by a sleeve 20 passing through the gear box casing 16, which latter is provided with a wall 21 attached to a super-structure 22 integral with the cap 4. The horizontal spindle 18 is spliced by means of a rubber coupling 23 to the output shaft 24 of a small, high-speed electric motor (not shown) mounted in suitable housing 25 attached to the super-structure by means of a claw mechanism 25a which permits its removal. A pistol-grip handle 26 depends from the housing and a switch 27 for the motor is mounted in the handle.

A "trigger" 28 is disposed between the handle 26 and the paint container 1 and is rigidly connected to a spindle 29 carrying an arm 30 which passes through a gland 30a in the superstructure 22. The end of arm 30 rests on the upper surface of a collar 31 attached to the collinear tube 7. The arrangement is such that pressure on the "trigger" 28 lowers the collinear tube to close the gap 9 between it and the feed tube 5, whilst release of the "trigger" causes the collinear tube

7 to rise under the influence of the elasticity of the spider 8 carrying it.

Surrounding the upper end of the collinear tube 7 is a hemispherical feed centrifuge 32 having a hole in its centre through which the collinear tube passes. The mouth of the centrifuge is directed upwardly and it is carried by a spider 33 attached by a spring clip 34 to the vertical spindle 14.

A third bevel-gear wheel 35 (see Figs. 3 and 4) within the gear-box casing 16 engages the horizontal gear wheel 15 and is mounted on a horizontal spindle 36 to which it is held by a spring clip 37. This spindle is set at an angle of 95° with the axis of the horizontal spindle 18 and passes through the gear-box casing; it carries two partially-hemispherical concentric cup-like atomising centrifugal elements 38 and 39 disposed one within the other attached to the spindle 36 by a spring clip 36a, and hereinafter referred to as a "bank" of centrifuges. A fourth bevel-gear wheel 40 is mounted on the vertical spindle 14 to which it is held by a spring clip 41 and this wheel engages with a fifth bevel-gear wheel 42 (see Fig. 4) mounted and held in position by a spring clip 43 on a horizontal spindle 44 which is set at an angle of 95° with the axis of the horizontal spindle 18 and on the opposite side thereof to spindle 36. Spindle 44 also passes through the gear-box casing and has a bank of two partially-hemispherical cup-like atomising centrifugal elements 45 and 46 mounted on it and attached thereto by means of a spring clip 44a (see Fig. 4). The two banks of atomising centrifugal elements 38, 39 and 45, 46 are arranged with their mouths facing inwards and the inner centrifugal elements 38, 45 of the banks are of such a size as to surround parts of the rim of the feed centrifuge 32 on opposite sides. Both centrifuges have a common centre of curvature which is coincident with that of the gear-box casing 16. The outer centrifugal elements 39, 46 have shields 39a, 46a formed at their centres to prevent paint reaching the bearings of shafts 36 and 44 respectively.

The vertical spindle 14 carries a sixth bevel-gear wheel 47 mounted above and integral with gear wheel 40. Gear wheel 47 meshes with a seventh bevel-gear wheel 48 carried by a spindle 49 mounted in a sleeve 50 passing through the gear-box casing. The axis of spindle 49 passes through the common centre of curvature and lies substantially in the same plane as the axis of the feed centrifuge 32 between the two banks of atomising centrifuges at an angle of about 60° to the horizontal. A hemispherical controlling centrifuge 51 having an aperture in its base is mounted on spindle 49 by means of a three-armed spider 52 and boss 53 held by a spring clip 54. The centre of curvature of this centrifuge is coincident with the common centre of curvature and its diameter is such that it surrounds parts of the rim of the two outer atomising centrifugal elements 39 and 46 of the two banks.

The super-structure 22, integral with the cap 4, comprises a casing 55 (see Figs. 3 and 4) for the centrifuges having an orifice 56 opposite to the aperture in the controlling centrifuge 51. The cap and super-structure may conveniently be formed by die-casting.

A circular shield 57 (see Figs. 1 and 2) is provided operating as a valve to seal the paint container 1 from the centrifuges when the "trigger" 28 is in the release position. This shield is attached to the collinear tube 7 and its rim rests

on a seating 58 forming part of the super-structure. Should the apparatus be knocked over paint cannot reach the centrifuges except through the collinear tube.

5 In operation, with the electric motor switched on, a drive is applied to bevel-gear wheel 17 which causes rotation at high speed of the vertical spindle 14, the vertical shaft 10 and of all the centrifuges. The Archimedean screw lifts 10 paint up the tube 5 and, with the "trigger" 28 in its released position, this paint spills over the top of the tube 5, through the gap 9 in the feed tube between the tube 5 and the collinear tube 7, back into the container 1.

15 On applying pressure to the "trigger," the collinear tube 7 is lowered to close the gap 9, whereupon paint is lifted to the top of the collinear tube, where it spills over the upper end into the feed centrifuge 32. The paint rises up the 20 interior of this centrifuge to its periphery and is thrown outwardly in a horizontal plane in all directions. Some of the paint is caught by the 25 two banks of atomising centrifugal elements 38, 39 and 45, 46 where it travels towards their rims, leaving them in four vertical planes as sprays, indicated by the lines 59, tangential to the rims, flying off in all directions. Paint thrown off by the feed centrifuge 32 not collected by the atomising centrifuges falls back into the container.

30 Part of the spray from the atomising centrifuges travels out through the aperture in the base of the controlling centrifuge 51, part falls on this centrifuge and the remainder falls back into the container. The paint that falls on to 35 the centrifuge 51 is also returned from its rim to the container, but the spray that passes through the aperture travels out of the orifice 56 and deposits on the work to be painted. The effect of the controlling centrifuge is to act as a screen or 40 shield to ensure a beam of paint spray of useful cross-section and also to prevent dripping.

45 Each bank of atomising centrifuges may comprise three or more partially-hemispherical cup-like centrifugal elements arranged concentrically with one another, all but the outer centrifugal element of each bank having apertures in their bases to permit liquid to reach each of them. These apertures are of progressively decreasing 50 diameters from the inner centrifugal element to that next to the outer centrifugal element. Alternatively each bank may comprise one atomising centrifugal element only.

The arrangement of spindles 36 and 44 with 55 their axes of rotation intersecting at the common centre of curvature at an angle of about 170°, instead of being in line, has the effect of causing the two beams of spray thrown off in the direction of the orifice 56 to be convergent to focus on to the work to be painted.

60 As the centrifuges are surrounded by the casing which has only the one orifice 56, the spray of liquid from the atomising centrifuges will only be accompanied by the relatively small air volume entrained by the movement of the atomised

65 liquid itself as compared with previously known constructions in which the atomiser is arranged to operate also as or with a fan to produce an air stream to carry the atomised liquid. It is known that any such air stream ultimately builds 70 against the surface receiving the spray and forms a moving air barrier through which the atomised liquid has to pass to reach such surface. Consequently, the reduction of the volume of air accompanying the spray of liquid reduces

75 such barrier and also reduces the loss of fine

spray previously carried away by such moving air barrier. Thus there is greater economy of liquid, more effective application to the surface to be sprayed and less noxious atmosphere for the operator.

The centrifuges may be of any cup-like form, for example, conical. If the aperture in the controlling centrifuge 51 is circular, the emerging beam will be sharply defined; by modifying its shape, e. g. by making it square, the edges of the beam may be reduced in density thus enabling paint to be overlapped. The atomising centrifuges may have their rims of wave-like shape by being serrated or waved and thereby provide portions of their rims in parallel planes of revolution in order to give spread to the beam laterally of the plane of revolution of the rims of the atomising centrifuges.

What I claim is:

1. A spray-producing apparatus for liquids comprising a cup-like feed centrifuge, means for rotating said feed centrifuge about a substantially vertical axis and having its mouth directed upwardly, a cup-like atomising centrifuge, means for rotating said atomizing centrifuge about an axis at right angles to the axis of the said cup-like feed centrifuge and disposed with a part of the rim of said cup-like feed centrifuge within it, a cup-like controlling centrifuge, means for rotating said controlling centrifuge about an axis lying substantially in the same plane as the axis of the cup-like feed centrifuge and passing through the axis of said cup-like atomising centrifuge, disposed to surround part of the rim of said cup-like atomising centrifuge and having an aperture in its base intersected by the plane in which lies the rim of the atomising centrifuge, a casing surrounding all the said centrifuges and having an orifice also intersected by the plane in which lies the rim of the atomising centrifuge and in alignment with the aforesaid aperture so that liquid may pass therethrough after ejection from the rim of the atomising centrifuge and after passing through the said aperture in the controlling centrifuge, means for driving all said centrifuges, and means for feeding liquid to said cup-like feed centrifuge.

2. A spray-producing apparatus for liquids comprising a cup-like feed centrifuge, means for rotating said feed centrifuge about a substantially vertical axis and having its mouth directed upwardly, a cup-like atomising centrifuge, means for rotating said atomising centrifuge about an axis at right angles to the axis of the said cup-like feed centrifuge and disposed with a part of the rim of said cup-like feed centrifuge within it, a cup-like controlling centrifuge, means for rotating said controlling centrifuge about an axis lying substantially in the same plane as the axis of the cup-like feed centrifuge and passing through the axis of said cup-like atomising centrifuge, disposed to surround part of the rim of said cup-like atomising centrifuge and having an aperture in its base intersected by the plane in which lies the rim of the atomising centrifuge, a casing surrounding all the said centrifuges and having an orifice also intersected by the plane in which lies the rim of the atomising centrifuge and in alignment with the aforesaid aperture so that liquid may pass therethrough after ejection from the rim of the atomising centrifuge and after passing through the said aperture in the controlling centrifuge, means for driving all said centrifuges, means for feeding liquid to said cup-like feed centrifuge, including

a further cup-like atomising centrifuge, means for rotating the same, said further cup-like atomising centrifuge having its axis at right angles to the axis of the said cup-like feed centrifuge and disposed so as to have within it a part of the rim of said cup-like feed centrifuge other than that part already within the first cup-like atomising centrifuge and with its axis substantially in the same plane as the axis of the cup-like controlling centrifuge and first cup-like atomising centrifuge.

3. A spray-producing apparatus for liquids as claimed in claim 2 in which each of said two cup-like atomising centrifuges comprises a plurality of concentric cup-like elements spaced apart one within another, apertures being provided in the bases of all but the outermost cup-like elements to permit liquid from the feed centrifuge to reach each outer element through the aperture of the adjacent inner element.

4. A spray-producing apparatus for liquids as claimed in claim 2, wherein the axes of said two cup-like atomising centrifuges intersect one another at an angle of approximately 170 degrees in the aforesaid plane containing the axis of the controlling centrifuge.

5. A spray-producing apparatus for liquids as claimed in claim 2, wherein the rims of all the said atomising centrifuges are shaped wave-like to provide portions of the rim in parallel planes of revolution.

6. A spray-producing apparatus for liquids as claimed in claim 1, wherein said means for driving all said centrifuges comprises a gear-box disposed within said cup-like feed centrifuge, having an input shaft to which motive power may be supplied.

7. A spray-producing apparatus for liquids comprising a cup-like feed centrifuge, means for rotating said feed centrifuge about a substantially vertical axis and having its mouth directed upwardly, a cup-like atomising centrifuge, means for rotating said atomising centrifuge about an axis at right angles to the axis of the said cup-like feed centrifuge and disposed with a part of the rim of said cup-like feed centrifuge within it, a cup-like controlling centrifuge, means for rotating said controlling centrifuge about an axis lying substantially in the same plane as the axis of the cup-like feed centrifuge and passing through the axis of said cup-like atomising centrifuge, disposed to surround part of the rim of said cup-like atomising centrifuge and having an aperture in its base intersected by the plane in which lies the rim of the atomising centrifuge, a casing surrounding all the said centrifuges and having an orifice also intersected by the plane in which lies the rim of the atomising centrifuge and in alignment with the aforesaid aperture so that liquid may pass therethrough after ejection from the rim of the atomising centrifuge and after passing through the said aperture in the controlling centrifuge, means for driving all said centrifuges, and means for feeding liquid to said cup-like feed centrifuge, said means for feeding liquid to said cup-like feed centrifuge comprises a feed tube, an Archimedean screw disposed therein, both said feed tube and screw dipping into the reservoir aforesaid and means for driving said screw from said gear-box, said feed tube having a gap from said Archimedean screw to said cup-like feed centrifuge, said gap permitting the return of liquid to said reservoir when not required to be converted into spray, together with means for closing and open-

ing said gap, including actuating means therefor under the operator's control.

3. A spray-producing apparatus for liquids as claimed in claim 1, wherein the aperture in said controlling centrifuge is non-circular in shape. 5
